UNITED STATES PATENT OFFICE.

ALONZO C. GOODRICH, OF CHICAGO, ILLINOIS.

ADJUSTABLE GOLF-CLUB.

1,250,301.

Specification of Letters Patent. Patented Dec. 18, 1917.

Application filed August 13, 1914. Serial No. 856,517.

To all whom it may concern:

Be it known that I, ALONZO C. GOODRICH, a citizen of the United States, and a resident of the city of Chicago, in the county of Cook 5 and State of Illinois, have invented certain new and useful Improvements in Adjustable Golf-Clubs; and I do hereby declare that the following is a full, clear, and exact description of the same, reference being had 10 to the accompanying drawings, and to the numerals of reference marked thereon, which form a part of this specification.

This invention has for its object the construction of a golf club, the head of which 15 is adjustable through various angles whereby the many different shots played in the game of golf may be made, by the use of only a single club, thus obviating the inconvenience of carrying a number of different clubs, and 20 as well simplifying the game in many other respects. Clubs with adjustable heads have been constructed heretofore, but generally the heads have not fitted snugly to the shaft of the club, and consequently the looseness 25 or slight play present, has made the club objectionable and consequently such clubs have not come into general use. Another objection to clubs with an adjustable head has been due to the fact that when the head has 30 been adjusted the lower line or edge of the striking face of the club has been moved out of alinement with the shaft to such an extent that a different swing is required in order to strike the ball correctly.

35 It is an object of this invention to construct an adjustable golf club wherein the head is pivotally mounted upon the end of the club shaft, and with the disposition and arrangement of the parts being such that 40 the pivotal movement of the head into its various adjusted positions only moves the lower edge of the club a negligible amount with respect to its relation to the axis of the shaft.

45 It is also an object of this invention to provide and improved means for adjusting the head of a club relative the shank on which it is pivotally mounted, so that adjustment of the head may be made in a 50 very short space of time and without inconvenience.

55 It is furthermore an important object of this invention to construct a golf club wherein the head is pivoted at the heel of the club on an axis which is substantially alined in a plane through the axis of the

shank of the club, thus maintaining the lower edge of the club properly positioned with respect to the shaft in practically all 60 positions of adjustment.

It is finally an object of this invention to construct an adjustable golf club wherein a simplified means is provided for effecting the various adjustments, said means acting to hold the head of the club rigidly in its 65 various positions, and yet permitting adjustment from time to time as desired, and with no inconvenience whatever.

The invention (in a preferred form) is illustrated in the drawings and hereinafter 70 more fully described.

In the drawings:

Figure 1 is a rear view of the lower end of a golf club, the shaft being omitted, showing an adjustable head mounted on the 75 shank.

Fig. 2 is a top plan view thereof with the head broken away.

Fig. 3 is a fragmentary section taken on line 3—3 of Fig. 2. 80

Fig. 4 is a section taken on line 4—4 of Fig. 3.

Fig. 5 is a view similar to Fig. 4, showing a modified form of construction.

Fig. 6 is an end view of the inner end of 85 the head.

Fig. 7 is an end view of the lower portion of the shank, on which said head fits.

As shown in the drawings:

The reference numeral 1, indicates the 90 shank of a club, which is adapted to receive the shaft therein (not shown) and integral with the lower end of said shank is an extension 2, which is angled slightly with respect to the axis of the shank, as shown 95 clearly in Figs. 1 and 2, and is flanged over on its upper edge and provided with a downwardly directed tongue 3. Another tongue 4, is provided on the contact surface of said extension 2, said respective tongues 3 and 4, 100 being curved in the form of an arc concentrically about the center of a slot 5, cut in the heel or lower end of said extension 2. A pair of pins, denoted respectively by the reference numerals 6 and 7, are mounted in 105 radial recesses in said flanged portions of the extension 2, and each is provided with a shank 8, which projects through an aperture in the flanged portion of said extension 2, and on its upper end is provided with a 110 head 9.

Small spiral compression springs 10, are

mounted within the recesses of said flanged portion of the extension 2, and are wound about the shank 8, of the locking pins in order to normally impel the same downwardly, the same being limited in their movement by the heads 9. The head of the club, which is pivotally attached to the shank is denoted as a whole by the reference numeral 11, and is provided with recessed portions engaging the respective tongues 3 and 4, of the extension 2, of the shank. Said head 11, at its inner end is provided with two radially directed recesses 12, either one of which is adapted to be engaged by either one of said respective locking pins 6 and 7. Consequently, the head 11, is capable of being moved into four different adjustments. Substantially in alignment with the lower edge of the head 11, a gudgeon pin 13, is formed integrally thereon, adapted to engage in the slot 5, of the extension 2, said connection affording a pivot center for movement of the head upon the shank.

In the modification of my invention illustrated in Figs. 5, 6, and 7, I provide a shank 14, provided with an integral extension 15, which has a groove 16, in the upper flanged portion thereof, and a tongue 17, on the contact face thereof, said groove and tongue of course being disposed in a curve concentric about the center of a slot 18, in the lower end of the extension. A head 19, is provided with a gudgeon or pivot pin 20, adapted to engage in the slot 18, and is provided with a curved tongue 21, on the upper end thereof to engage the groove 16, and a recess to engage the tongue 17, of the shank. However, in place of the spring impelled locking pins of the prior construction, I provide a series of worm gear teeth 22, in the face of the extension 15, arranged concentrically about the center of the slot 18, disposed in the form of a rack, and, journaled in the head 19, is a worm 23, adapted to mesh with the teeth in the surface of the extension 15, to move the head into various adjusted positions with respect to the shank of the club. A squared end portion 24 is provided on said worm shaft in order to permit engagement thereof by a suitable tool or even the fingers of the user to rotate the worm, thereby adjusting the head 19, into its various angled positions.

The operation is as follows:

In the construction illustrated in Figs. 1 to 4 inclusive, an adjustment movement of the head 11, is effected by elevating the particular locking pin 6 or 7, as the case may be, which, at the time, holds the head 11, in a locked adjusted position, and the head may then be moved about its pivot 13, into another position, and of course one of the pins 6 or 7, as the case may be, clicks into

engagement with one of the recessed portions 12, of the head to hold the same in the adjusted position desired. It is of particular note that the extension 2, is not at right angles to the leading or lower edge of the head of the club, and accordingly said extension 2, receives a certain amount of the stress imposed upon the device when a blow is struck, thereby relieving the locking pins and pivot pin, to a certain extent, of the shearing stress imposed thereon.

In the modification of my device illustrated in Figs. 5, 6, and 7, I have shown a worm and tooth means of adjusting the head of the club through practically any desired angle of adjustment, the adjustment being attained merely by rotation of the worm 23, which, engaging the worm teeth 22, of the shank extension, effects the adjustment, and as well locks or holds the head so adjusted.

I am aware that various details of construction may be varied through a wide range without departing from the principles of this invention, and I therefore do not purpose limiting the patent granted otherwise than necessitated by the prior art.

I claim as my invention:

1. In a device of the class described a shank, an extension integral therewith and angled thereto, a head having pivotal engagement in a slot in the lower end of said extension, coacting concentric tongue and grooves on said head and extension to retain the same in various positions of adjustment, and a plurality of spring impelled locking means projecting through said extension adapted to lock said head in various positions of adjustment.

2. In a device of the class described a shank, an extension integral therewith having an open slot in the lower end thereof, a head pivoted on said extension, a plurality of spring impelled locking means mounted in said extension adapted to lock the device in various positions of adjustment, concentric coacting tongue and grooves on said head and extension to guide and retain the same in various positions of adjustment, and a gudgeon pin on said head adapted to freely engage said slot to afford a pivot center for adjustment of the head.

3. In a golf club of the class described a shank adapted to receive a golf stick secured therein, an extension on said shank, a striking head pivoted thereto, said extension angled with respect to the axis of said shank, a curved grooved flange formed on said head, a curved tongue formed on said extension adapted to interfit the grooved flange of said head to guide the head in its movement, another curved flange of less radius formed on said extension and interfitting another groove on said head, and spring controlled means project-

ing through said extension maintaining said head in different positions on said extension.

4. In a golf club of the class described the combination with a shank and extension integrally formed thereon, of a plurality of concentric curved tongues formed on said extension, a head releasably pivoted on said extension and having grooves therein interfitting with said tongues to guide the head 10 in adjusting movements on said extension,

and means projecting through said extension holding said head in various adjusted positions on the shank.

In testimony whereof I have hereunto subscribed my name in the presence of two 15 subscribing witnesses.

ALONZO C. GOODRICH.
